UNITED STATES PATENT OFFICE.

HENRY CLEMENT, OF RISING SUN, INDIANA.

IMPROVEMENT IN LIFTING-JACKS.

Specification forming part of Letters Patent No. 124,721, dated March 19, 1872.

To all whom it may concern:

Be it known that I, HENRY CLEMENT, of Rising Sun, Ohio county, State of Indiana, have invented a new and useful Improvement in Wagon-Jacks.

To enable others to make my wagon-jack I will proceed to describe its formation, referring to the drawing of the several parts of same hereto attached and forming part of this specification.

Letter A represents a perspective drawing of my wagon-jack as it stands ready for use, being the usual height of jacks used for the same purpose. It consists of two upright pieces, B B, of similar construction, made of wood or iron, having two movable legs, C C, which admit of being extended at each side of the upright pieces B B or slid back between the upright pieces, when not in use, and held in position by rods or bolts running through them and fastened by screws S S. The tops of these legs bear against a center bolt, D, running through and holding the uprights B B together; they are held and hindered from extending beyond the bolt by bearing against it and against each other so that they cannot

spread out further. The center bolt D, held by the screw h, has attached to it a movable stay or brace rod, G, which extends over and acts on the lever E at the notches g g g, made at certain required distances, and so adjusted as to suit the height of the wagon, dray, or other vehicle, holding the lever in the required position. E is the lever for raising the vehicle when the wheel is required to be put on or taken off, and acts between the upright pieces B B at e e e e and held there by a movable iron pin, F, running through the upright pieces.

What I claim as my invention is—

A wagon-jack consisting of two upright pieces, of wood or iron, having movable legs extending laterally, and a lever held in position by a stay or brace rod acting in notches, arranged to act substantially as and for the purpose hereinbefore set forth and described.

In testimony that I claim the foregoing invention I have hereunto set my hand and seal this 23d day of January, 1872.

HENRY CLEMENT.
